DOORKNOB LOCK

Fred E. Schneider, Grand Junction, Colo.

Application September 6, 1935, Serial No. 39,466

3 Claims. (Cl. 70—149)

This invention relates to door knob locks, and has for its principal object the production of a simple and efficient door knob lock, certain parts of which may be moved into and out of clutching engagement with the roll-back of the conventional door lock whereby the latching bolt of the door lock may be actuated.

A further object of this invention is the production of a door knob lock, having a conventional key operated barrel lock carried by one knob for selectively moving certain parts of the door knob lock into clutching engagement with the roll-back of a conventional door lock whereby the latching bolt of the door lock may be moved. Another object of this invention is the production of a simple and efficient door knob lock which may be actuated manually without a key from the inside of the door, and which may be operated through the insertion of a key in a barrel lock carried by the knob from the outside of the door.

Other objects and advantages of the present invention will appear throughout the following specification and claims.

In the drawing:—

Figure 1 is a horizontal sectional view through a portion of the door showing the improved door knob lock partly in section;

Figure 2 is a section taken on line 2—2 of Figure 1, the parts being shown in a released or free position;

Figure 3 is a section similar to Figure 2 showing the parts in a locking position in engagement with the roll-back;

Figure 4 is a transverse section taken on line 4—4 of Figure 2;

Figure 5 is a transverse section taken on line 5—5 of Figure 2;

Figure 6 is a transverse section taken on line 6—6 of Figure 2;

Figure 7 is a transverse section taken on the line 7—7 of Figure 3;

Figure 8 is a perspective sectional view of the shank of the knob and the cooperating parts, a portion of the lock casing and roll-back being also shown;

Figure 9 is a perspective view of one of the sliding clutching plates;

Figure 10 is a longitudinal section through the barrel lock supporting casing showing a modified form of spiral groove and lug connection between the barrel lock and clutching plate.

By referring to the drawing it will be seen that D designates the door, which carries the usual or conventional lock casing L. This lock

casing L also carries the conventional roll-back 10, which roll-back 10 is provided with a rectangular or square central aperture 11.

The squared stem or rectangular stem or shank 12 of the door knob carries at its respective ends the knobs 13 and 14. The shank 12 is provided with an intermediate portion 15 which is reduced in thickness to allow the intermediate portion 15 to freely rotate within the squared aperture 11 of the roll-back 10 when the parts are in the 10 position shown in Figures 2 and 8.

A clutching plate 16 is slidably mounted through casing 17 carried within the knob 14 as shown in the drawing, and this clutching plate 16 is connected to a key actuated barrel lock 18 which is fitted within the enlarged outer end 19 of the casing 17, the outer end of the barrel lock 18 preferably being flush with the outer end of the knob 14, as shown. A suitable key 20 of the conventional type may be utilized for actuating the barrel lock 18 which is also of the conventional type. The mechanism of the barrel lock 18 is connected to the clutching plate 16 by means of an extending finger 21 shown in the drawing. This plate 16 may be longitudinally slotted, as 25 at 22, and a securing pin 23 extends through the shank of the knob 14 and through one of the selected apertures 24 of the stem or shank 12 thereby permitting the plate 16 to shift longitudinally and also to firmly secure the knob 14, 30 the casing 17 and the stem or shank 12 in position. The clutching plate 16 is provided with a pair of parallel right angularly extending ears 25 which straddle the intermediate reduced portion 15 of the stem or shank 12, note particularly 35 Figure 8. When the barrel lock 18 is unlocked through the medium of the key 20, the plate 16 will be shifted longitudinally to a position where the ears 25 will fit snugly within the aperture 11 of the roll-back 10, thereby causing the roll-back 40 10 to be rotated when the knob 14 is rotated, and consequently, actuate the conventional latch bolt of the lock L. It is thought unnecessary to show the latching bolt of the lock L due to the fact that this is of a conventional type. The barrel 45 lock 18 may be of the conventional spring type which will cause the plate 16 to be shifted inwardly when the lock 18 is actuated through the medium of the key 20, and when the key is moved to a locked position the plate 16 is adapted to be 50 drawn outwardly with respect to the roll-back 10. Since the lock 18 is of the conventional type it is thought also unnecessary to illustrate the particular structure embodied in the lock 18 since any conventional lock of this type may be utilized.

The knob 13 is provided with a socket 26 into which fits the opposite end 27 of the stem or shank 12 and a manually operated clutching plate 28 is slidably mounted within the longitudinally extending aperture 29 formed in the knob 13. This clutching plate 28 may be provided with a laterally turned end 30, to facilitate the gripping of the plate 28 by one finger of the operator. This plate 28 may be longitudinally slotted, as at 31, and a securing screw 32 is extended through the shank 33 of the knob 13 for connecting the end 27 of the stem 12 in engagement with the knob 13, this screw 32 also extending through the slot 31 and allowing the clutch plate 28 to be longitudinally adjusted. The plate 28 is provided with a pair of parallel right-angularly bent ears 34 similar to the ears 25, which ears straddle the reduced portion 15 of the stem or shank 12, as shown in Figure 8. By shifting the plate 28 inwardly the ears 34 may be forced into the aperture 11 of the roll-back 10 and causes the stem or shank 12 to be locked in engagement with the roll-back 10 whereby the roll-back 10 may be rotated when the knob 13 is rotated.

As shown in the drawing, it will be obvious that the barrel lock 18 which is carried by the knob 14 is preferably located on the outside of the door so that the clutching plate 16 may be only actuated and moved to an operative position through the insertion of the key 20 into the lock 18 and by a proper manipulation of the key. However, the plate 28 may be manually operated by the fingers of the operator from the inside of the door thereby avoiding the necessity of utilizing a key to shift the plate 28 to and from an operative position or to a clutching position with respect to the roll-back 10.

As shown in Figure 10, the barrel lock 18a may be provided with a central bolt 21a having a spiral groove 35 into which fits the lug 36 on the inner end of the clutching plate 16a. This structure may form a connection for the clutching plate and barrel lock bolt and may be considered preferable to that illustrated in Figure 8.

Having described the invention what is claimed as new is:

1. A door knob lock of the class described comprising a stem, a roll back having a rectangular passage formed therethrough, said stem having a reduced shank extending through the passage of said roll back and freely rotatable therein, the enlarged end portions of the stem defining shoulders at opposite sides of the end of the shank, a knob fitting about an end portion of said stem and connected with the stem to turn the stem with the knob, a clutching plate slidably mounted for movement longitudinally of the stem in said knob and having a portion extending along the shank and provided with side ears straddling the shank and disposed against opposite sides thereof and adapted to engage the shoulders to limit outward sliding movement of the clutch plate, said ears being adapted to move into the passage of said roll back and engage the walls thereof to cause the roll back to turn with the stem when the clutching plate is slid longitudinally of the stem in one direction, and said clutching plate having a portion projecting from the outer end of said knob and bent to form a portion projecting laterally and constituting a finger-engaging element whereby the clutching plate may be pressed inwardly to shift the ears into the passage of the roll back.

2. A door knob lock of the class described comprising a stem, a roll back having a rectangular passage formed therethrough, said stem having a reduced shank extending through the passage of said roll back and freely rotatable therein, the enlarged end portions of the stem defining shoulders at opposite sides of the end of the shank, a knob fitting about an end portion of said stem and connected with the stem to turn the stem with the knob, a clutching plate slidably mounted for movement longitudinally of the stem in said knob and having a portion extending along the shank and provided with side ears straddling the shank and disposed against opposite sides thereof and adapted to engage the shoulders to limit outward sliding movement of the clutch plate, said ears being adapted to move into the passage of said roll back and engage the walls thereof to cause the roll back to turn with the stem when the clutching plate is slid longitudinally of the stem in one direction, a lug carried by the outer end of said clutching plate, and a barrel lock mounted in said knob and having a rotatable bolt formed with a spiral track receiving said lug and causing the clutching plate to be shifted longitudinally when the bolt is rotated.

3. A door knob lock of the class described comprising a roll back having a rectangular passage formed therethrough, a stem having its intermediate portion reduced in width to provide a flat sided shank connecting enlarged end portions providing shoulders at opposite sides of ends of the shank, the shank of the stem passing through the passage of said roll back and freely rotatable therein and of greater length than the passage of the roll back to dispose the shoulders in spaced relation to ends of the roll back, a knob formed with a pocket receiving the enlarged end portion of said stem, a clutching plate extending longitudinally of the stem against the enlarged portions thereof and having side ears straddling the shank of the stem and engaging opposed flat faces thereof between the roll back and the shoulders and adapted to engage the shoulders and limit outward sliding movement of the clutch plate, said plate extending into the knob beyond the end of the stem and being formed with a longitudinally extending slot, a pin extending transversely through the knob and the enlarged end portion of the stem and passing through the slot to mount the plate for sliding movement and hold the knob in fixed engagement with the stem, and means for imparting sliding adjustment to said plate and moving the ears thereof into the passage of the roll back for gripping engagement therewith to cause turning of the roll back with the stem and knob.
